UNITED STATES PATENT OFFICE.

JOHN J. BERRIGAN, OF ORANGE, NEW JERSEY.

CENTRIFUGAL SEPARATOR.

No. 827,903.

Specification of Letters Patent.

Patented Aug. 7, 1906.

Application filed November 7, 1905. Serial No. 286,194.

To all whom it may concern:

Be it known that I, JOHN J. BERRIGAN, of Orange, Essex county, New Jersey, have invented a new and useful Improvement in 5 Centrifugal Separators, of which the following is a specification.

The invention relates to centrifugal separators for solids and liquids.

The principle of the invention consists in 10 subjecting the combined solids and liquids to separation in order to remove the greater part of the liquid, then conveying the residual solid, with such liquid as may remain combined with it, through a series of frusto-conical chambers disposed in a rotary cylinder, with their common central axis parallel to the cylinder-axis of rotation, (and hence eccentrically placed in said cylinder,) in each of which chambers the solid materials are 15 20 first projected outwardly centrifugally and then moved centripetally to the central outlet leading to the next chamber. The liquid accumulates at the point of greatest eccentricity of each chamber and may escape 25 therefrom by an independent outlet therein, and the solid material is dried by being conveyed out of the accumulated liquid in each chamber and around the substantially dry inner periphery thereof, while at the same 30 time it is moved onward to the chamber next in succession, and finally to the outlet from the machine.

The invention consists in the construction hereinafter set forth, which embodies said 35 principle, and in the particular combinations recited in the claims.

In the accompanying drawings, Figure 1 is a vertical longitudinal section of the machine. Fig. 2 is an enlarged similar section of 40 the feed end of the machine. Fig. 3 is a section on the line 3 3 of Fig. 1.

Similar numbers and letters of reference indicate like parts.

1 is a horizontal cylinder within which the 45 working parts of the machine are inclosed. On the head 2 of said cylinder is a hollow trunnion, received in a bearing in the fixed standard 3. Bolted to the opposite head 4 of said cylinder is a cylindrical casing 5, on 50 which is formed a hollow trunnion, which is received in a bearing in the fixed standard 6. Standards 3 and 6 rest upon the bed 7 of the machine. The driving-pulley 8 is fast upon the cylinder-trunnion. Power is communicated to said pulley by any suitable belt,

(not shown,) and in that way cylinder 1 is caused to rotate.

9 is the feed-hopper, supported on bracket 10, extending from standard 3.

The combined solid and liquid materials to 60 be separated are conveyed into the cylinder 1 by means of a screw conveyer 11, the shaft of which is supported at one end in a bearing on the bracket 10 and carries the sprocket-wheel 12. The other end of said conveyer-shaft is stepped in a wall of a chamber 13, formed upon the inside of the head 2, which chamber by means of the inclined duct 14 communicates with the interior of a cylinder 15, which is eccentrically disposed within the 70 cylinder 1 and supported therein by the blocks 16 and ring 17. One end 18 of the cylinder 15 is frusto-conical and communicates with an outlet-duct 19, which extends through the wall of cylinder 1 and communicates with the fixed annular chamber 20, in which the cylinder 1 freely turns.

Passing through the hollow trunnion at the delivery end of the machine and entering the casing 5 is a shaft 21, which is held in stationary position by a lever-arm 22, fast on the outer end of said shaft, which lever-arm is connected by a rod 23 with the bed of the machine. Any other convenient means may be used for holding said shaft stationary. 85 Within the casing 5 the shaft 21 carries a pinion 24, which engages with a pinion 25 on a shaft journaled in the casing-head and the head 4 of cylinder 1. On the same shaft as pinion 25 is a pinion 26, which engages with a 90 gear 27 on the end of a shaft 28, which extends axially through the cylinder 15. Said shaft 28 is supported in roller-bearings in sleeves 29 and 30, formed, respectively, on the head 4 of cylinder 1 and the wall of chamber 13, 95 the said sleeves being provided with annular covers, as shown.

Within the cylinder 15 are a number of supporting-rings 31, and secured to each of said rings is a frusto-conical partition 32 33 100 34. These partitions divide the interior of cylinder 15 into successive separating chambers or compartments A B C D. The smaller openings of said partitions are larger than the shaft, so that around said shaft there is 105 an annular space through which the material being treated may pass from one compartment to the next.

On the shaft 28 are arms 35, which carry bars 36, upon which bars are secured convey-

ing-scrapers 37. Some of these scrapers act upon the material which is centrifugally deposited on the inner side of the wall of cylinder 15 and others act upon said material deposited on the inner peripheries of the frusto-conical partitions therein.

In the cylinder-head 2 is an opening 39 for the escape of liquid into the annular fixed chamber 40, from which said liquid escapes 10 by any suitable outlet. Passing through the walls of both cylinders 1 and 15 and entering the separating-chambers B C D are open tubes 41. There may also be an opening 42 in the cylinder-head 2 near to the center thereof.

On the hub of the driving-pulley 8 is a sprocket-wheel 42, which by means of the belt 43 transmits motion to a sprocket-wheel 44 on the end of shaft 45, which extends 20 through the bed 7 of the machine and carries at its farther extremity a sprocket-wheel 46, which by chain belt 47 rotates sprocket-wheel 12.

When the driving-pulley 8 is rotated, the cylinder 1 is caused to turn on its trunnions, thus carrying the gear 25 in planet movement around the fixed pinion 24. Gear 25, and hence pinion 26 on the same shaft, is thus rotated, and from pinion 26 motion is communicated to shaft 28 to cause the scrapers to be carried around the inner surfaces of the cylinder 15 and conical partitions at a rate of speed different from that of the rotation of cylinder 1. The feed-conveyer 11 is 35 set in rotation by the sprocket-chain 47.

The operation of the machine is as follows: The combined solid and liquid materials to be separated are introduced into the hopper 9 from the pipe 48, and thence by means of the screw conveyer 11 are carried into the chamber 13, whence by the pipe 14 they are delivered into the first separating-chamber A in cylinder 15. By reason of the eccentricity of cylinder 15 to the axis of rotation of cylinder 1 the liquid is projected by the centrifugal force of rotation to that part of the inner surface of cylinder 15 which is farthest distant from said axis of rotation, as indicated at F, Fig. 3. The radial depth of liquid here 45 accumulating cannot exceed the distance of the outlet 39 from the cylinder-wall, and hence said liquid flows from said outlet to the chamber 40 and thence to any convenient receptacle. The solid material is carried out 50 of the liquid and around the inner cylindrical periphery of chamber A by the scrapers 37, which also convey it over the inner surface of partition 32 to the central outlet, whence it passes to the second separating-chamber B. 55 Here the centrifugal force again throws whatever liquid may still remain combined with the solid to the most eccentric portion of said chamber, whence it drains through the small opening 49 to the surrounding annular chamber 50 and escapes at any suitable outlet.

The opening 49 may be so small as not to permit any considerable escape of solids, and yet be sufficient to allow the liquid to be projected out of it by centrifugal force. The solid is carried by the scrapers, as before, around 70 and through the chamber C, where the same operation is repeated, any contained liquid escaping at opening 51 to chamber 52. The materials then pass to chamber D, where another repetition occurs, and the residual liquid 75 escapes from opening 53 into chamber 54. Finally, the now substantially dry solid passes by the escape-duct 19 to the delivery-chamber 24.

Inasmuch as the eccentricity of the cylinder 80 15 results in the liquid being accumulated on one side of the inner surface thereof, it is obvious that the solids, which will be carried around the remainder of the cylinder periphery, will pass over a substantially dry 85 surface, and thus be rapidly dried by exposure to the atmosphere. The greater part of the combined liquid is removed in the first separating-chamber A, and the quantity in chambers B C D will be successively less and 90 very small in amount, so that while separation goes on in the successive chambers the drying operation progressively predominates.

The outer cylinder 1, with the supporting-blocks 16 and ring 17, operates to balance 95 the eccentric cylinder 15. Any number of frusto-conical partitions may be employed, depending on the number of separating-chambers A B C, &c., desired. The short tubes 41 serve to lead atmospheric air into cylinder 15 to cool the interior when hot materials are being treated.

I claim—

1. In a machine for separating solids and liquids, a rotary vessel, and a second vessel 105 eccentrically disposed therein; the said inner vessel having a plurality of chambers wherein solids are centrifugally projected to the inner surface thereof, and, alternating with said chambers, a plurality of devices for conveying said solids centripetally.

2. In a machine for separating solids and liquids, a rotary cylindrical vessel, a cylindrical vessel eccentrically disposed therein and, in said inner vessel, a plurality of frusto-conical partitions and means for conveying the material to be separated through said partitions successively and around the concave peripheral surfaces thereof.

3. A rotary vessel, a cylindrical vessel for separating solids and liquids eccentrically disposed therein, the said inner vessel having two communicating chambers, means for centrifugally separating out liquid in the first chamber, means for conveying the residual 120 solid and liquid materials, in a centripetal direction to said second chamber, means for projecting said residual materials outward centrifugally to cause a second separation to remove liquid in said second chamber and 125 130

means for conveying the second residue centripetally to an escape-opening in said inner vessel.

4. A rotary vessel, a cylindrical vessel eccentrically disposed therein, the said inner vessel having a series of frusto-conical separating-chambers with their inclined walls parallel and communicating at their smaller ends, each of said chambers having a liquid-outlet, means for feeding combined solid and liquid material into the large end of the first chamber, means for conveying centrifugally-deposited material through said chambers successively and means for centrifugally discharging solids from the last chamber.

5. In a separator for solids and liquids, a horizontal rotary cylinder, a second cylinder eccentrically fixed therein, and having a liquid-escape opening in one head, a series of

frusto-conical annular partitions in said inner cylinder, an axial shaft also in said inner cylinder, conveying-scrapers carried by said shaft and constructed to carry the material around the inner periphery of said inner cylinder and partitions and to deliver the same through the clearance-space between said partitions and shaft, means for feeding combined materials into the chamber between said cylinder-head and the first partition of the series and an outlet-duct for solids at the opposite end of said inner cylinder.

In testimony whereof I have signed my name to this specification in the presence of two subscribing witnesses.
